SLICING MACHINE

Thomas H. Strachan and William H. Fryer,
Dayton, Ohio, assignors, by mesne assignments,
to International Business Machines Corporation,
New York, N. Y., a corporation of New
York

Application September 25, 1931, Serial No. 565,090

2 Claims. (Cl. 146—102)

This invention relates to slicing machines in general, particularly to machines used to slice articles of food such as meat, bread, cheese, and like materials.

5 The general object of the invention is to provide an improved arrangement for varying the feed pressure of the material sliced whereby different kinds of materials may be fed to the knife at pressures best suited to the physical characteristics of the material to be sliced.

It is customary to provide slicing machines with a clamp mounted in a clamp carrier fed transversely of the knife and adapted to press the material to be sliced against a suitable gauge 15 plate which governs the thickness of the slices. The clamp carrier is usually slidably mounted in a carriage movable parallel with the knife during slicing operations and it is common practice to provide means for automatically feeding 20 the clamp carrier toward the gauge plate. One form of machine at present manufactured utilizes a spring actuated drum to effect the necessary automatic feed toward the gauge plate, the spring drum being concealed in the base of the clamp carrier and connected by a flexible tape to a fixed 25 part of the carriage so that the spring drum tends always to feed the clamp carrier toward the gauge plate.

An objectionable feature of constructions such 30 as the foregoing is the fact that all materials are fed to the gauge plate with the same pressure and some materials are pressed against the gauge plate with too much pressure owing to the fact that it is necessary to adjust the tension of the 35 spring drum during assembly to give the maximum feed pressure used with meats or like relatively dense firm materials. As a result bread and like soft materials are fed with too great a pressure resulting in mushrooming of the material, crumbling, and uneven slices.

It is a specific object of this invention to provide a machine of the type mentioned with simple and effective means for readily and at will varying the pressure of the feed whereby a feed 45 pressure may be used which is best suited to the physical characteristics of the material to be sliced.

Various other objects, advantages, or features 50 of the present invention will be pointed out in the specification and claims or will be clear after a study thereof and of the accompanying drawings.

In the drawings:

Figure 1 is a side elevation of the slicing machine.

Figure 2 is a front view of the carriage and clamp carrier with the food pan removed.

Figure 3 is a vertical section on the line 3—3 in Figure 2.

Figure 4 is a vertical section on the line 4—4 in Figure 2.

This invention is an improvement in the construction of the machine illustrated and described in application Serial No. 496,376, filed November 18, 1930 by W. H. Fryer, however, it is obvious that it may be applied to other machines as well and it is not desired to limit application of the invention to the specific machine described in said application.

The numeral 10 refers to the base of the slicing machine upon which is rotatably mounted the knife 11 and carries a gauge plate 12 which may be adjusted to regulate the thickness of the slices. The material to be sliced is held between a movable clamp element 13 and a fixed clamp element 14, both carried by the clamp carrier 15 which is slidably mounted on a cross bar 16 supported on the carriage 17. The latter is slidably mounted upon a rail 18 supported on posts 19 carried by the base and is provided with a handle 20 by means of which the carriage may be moved parallel with the knife to slice material held between the clamp elements 13, 14. There is provided the usual food pan 21 attached to the carriage 17.

The clamp element 13 is provided with prongs projecting downwardly and adapted to cooperate with similar prongs in clamp element 14 to enable said elements to firmly grip the material to be sliced. A portion of the clamp element 13 is bent upwardly and substantially parallel with the gauge plate 12 and is also provided with prongs similar to those in the element 14 for the purpose of holding impaled thereon pieces which are too thin to be held between the element 14 and the other portion of element 13 so that said pieces may be pressed toward the gauge plate in feeding them to the knife.

The element 13 is carried by a vertically slideable member 22 guided in an opening in the upper end of the clamp carrier 15 and provided with a knob or handle 23 by means of which the clamp element 13 may be raised to place the article to be sliced between element 13, 14.

The member 22 is notched as at 24 and these notches cooperate with a tooth in the end of a spring pressed plunger 25 carried by the member 22. When an article of food has been placed between the clamp elements 13, 14 the handle 23 may be pressed downwardly to apply pressure to the article to be sliced and during such downward

movement the tooth in the end of the spring pressed plunger 25 drops into the notches 24 and prevents the member 22 from being forced upwardly due to the resiliency of the material to be sliced. The article to be sliced is thus held securely between the clamp elements 13, 14.

The clamp carrier 15 is automatically drawn toward the gauge plate by means of a spring drum 26 mounted in the base of said carrier. The spring drum 26 is provided with a spiral spring 27 one end of which is connected to the said drum while the other end is connected to a stud carried by a bracket 28 fixed to the clamp carrier 15 at the base thereof. A tape 29 has one end thereof fixed to the periphery of the drum 26 and the other end of said tape is fixed to the periphery of a smaller drum 30 fast on a rotatable stud 31 journaled in the frame of the carriage at the end nearest the knife 11. It will thus be seen from Fig. 2 that, assuming the end of the tape nearest the knife to be fixed, the clamp carrier 15 will be drawn towards the gauge plate with a pressure which will always be the same regardless of the material to be sliced.

One of the features of this invention is the provision of means whereby the tension on the tape 29 may be varied to suit different materials to be sliced so that each material may be fed towards the gauge plate with a pressure suitable to the characteristics of the material and for this reason the drum 30 is made rotatable by increments sufficient to increase the tension in tape 29 to the desired value.

As shown in Figs. 2 and 3, the drum 30 is rotatably mounted on the bar 16 and is provided with teeth 32 cooperating with a pawl 33 mounted on the bar 16. The pawl 33 is fixed to the end of a knurled member 34 pivotally mounted on the bar 16 end is pressed into contact with the teeth 32 by means of a spring 35 carried by the bar 16. When it is desired to increase the tension of the tape 29 in order to apply greater feed pressure to the material to be sliced, it is merely necessary to turn the drum 31 in a direction to wind the tape 29 thereon which will result in partly unwinding the tape 29 from the drum 26 by rotation of the latter. Such winding of tape 29 on drum 30 will tend to tension the spring 27 so that the whole result will be that clamp carrier 15 will be fed toward the gauge plate with an increased pressure. The drum 30 may be very easily turned by means of a screw stud 36 screwed tightly into the stud 31 and also serving to hold stud 31 in bar 16. By inserting a screw driver in the slot of stud 36 the stud 31 may be readily turned to wind up the tape 29. It will be obvious that rotating the drum 30 in this fashion will cause the pawl 33 to drop into the teeth 32 of the stud 31 and prevent unwinding the tape 29 from the drum 30 due to the tension of spring 27.

Any number of teeth may be provided in the stud 31 within the limits of the amount the tape 29 may be unwound from the drum 26. When the drum 30 has been turned to secure maximum tension in the tape 29 and it is desired to use a lighter feed pressure, it is merely necessary to insert a screw driver in the slot of the screw stud 36 and then, after turning the knurled thumb piece 34 to release the pawl 33 from the teeth 32 of the stud 31, permit drum 30 to turn under the tension applied by the tape 29 until the desired feed pressure is obtained.

As a matter of convenience in determining the proper feed pressure to be used the bar 16

may have a graduated dial adjacent the stud 36 and a suitable mark provided in said stud cooperating with said dial to indicate the desired feed pressure.

In the construction described in the aforesaid application the spring drum 26 and its tensioning spring 27 are concealed in the base of the carrier 15 in front of the bar 16 and behind the food pan 21 so that access may not be readily had thereto to adjust the tension of the spring and it is impossible to apply ordinary methods of tensioning spring drums since the bar 16 prevents access to said drum from the rear and the clamp element 14 and food pan 21 prevents access thereto from the frame. The stud 36 located in the rear surface of bar 16 is readily accessible, however, and may be turned as described by means of a suitable screw driver or screw driver key. If desired, of course, the stud 36 may be squared to receive a suitable key or the key may be integral with said stud, however, the slotted screw 36 will undoubtedly be amply sufficient for most purposes.

The clamp carrier 15 is mounted by anti-friction means upon the bar 16 so that its feeding movement will be as free from friction as possible and is cut-away at 37 to accommodate the stud 31 when said carrier is drawn completely to the left (Fig. 2). The clamp carrier is limited in its movements lengthwise of the bar 16 by striking the frame of the carriage 17 adjacent the points where the bar 16 is fixed to said frame.

The embodiment of the invention shown in the drawings and described hereinbefore is purely illustrative of the form which the invention may take in practice and it is not desired to limit the scope of the invention to such embodiment as variations and modifications may be introduced to suit various conditions of practice or the different machines to which the invention may be embodied.

We claim:

1. A slicing machine having a knife and a carriage movable parallel therewith to slice an article on the carriage; clamping means for said article mounted for movement in said carriage in a direction transversely of the plane of the knife to feed the article to the knife; and feeding means for automatic feed of the clamping means, comprising a spring actuated drum concealed in the clamping means, and a tensioning device for said spring drum mounted in the carriage, said tensioning device including a drum connected to the spring actuated drum and manually rotatable to vary the tension of the latter in accordance with the physical characteristics of the article to be sliced.

2. A slicing machine having a knife and a clamping device for holding the article to be sliced, means for automatically feeding said clamping device to the knife comprising a spring actuated drum carried by the clamping device, an adjustable tensioning drum rotatably mounted on said means separately from the clamping device, a tape connecting said drums, means integral with the tensioning drum for rotating the latter in a direction to vary the tension of said tape whereby to vary the feed pressure of the clamping device, and manually releasable means for holding the tensioning drum in adjusted position.

THOMAS H. STRACHAN,
WILLIAM H. FRYER.
